CLAIM

The ornamental design for a hair extension package.

DESCRIPTION

FIG. 1 is a top plan view of a hair extension package; FIG. 2 is a bottom plan view thereof;

FIG. 3 is a right side-elevation view thereof;

FIG. 4 is a left side-elevation view thereof;

FIG. 5 is a front elevation view thereof; and,

FIG. 6 is a rear elevation view thereof.

Broken lines in FIG. 6 show a bar code label, and form no part of the claimed design.
